Primary Examiner — Cynthia Underwood(74) Attorney, Agent, or Firm — Belles Katz LLC(57) CLAIM

I claim the ornamental design for a bottle, as shown and described.

DESCRIPTION

FIG. 1 is a top front perspective view of a bottle according to the claimed design;

FIG. 2 is a bottom rear perspective view of the bottle of FIG. 1;

FIG. 3 is a front view of the bottle of FIG. 1;

FIG. 4 is a rear view of the bottle of FIG. 1;

FIG. 5 is a left-side view of the bottle of FIG. 1;

FIG. 6 is a right-side view of the bottle of FIG. 1;

FIG. 7 is a top view of the bottle of FIG. 1; and,

FIG. 8 is a bottom view of the bottle of FIG. 1.

All broken lines shown in the drawings are for environmental purposes only and form no part of the claimed design.
